UNITED STATES PATENT OFFICE.

HILARY FUDCZKO, OF PHILADELPHIA, PENNSYLVANIA.

METALLIC TIE AND RAIL-FASTENER.

1,314,956.

Specification of Letters Patent.

Patented Sept. 2, 1919.

Application filed December 27, 1918. Serial No. 268,481.

To all whom it may concern:

Be it known that I, HILARY FUDCZKO, a citizen of the United States of America, residing at Philadelphia, in the county of Philadelphia and State of Pennsylvania, have invented certain new and useful Improvements in Metallic Ties and Rail-Fasteners, of which the following is a specification.

10 The primary object of the invention is the provision of a metallic tie upon which rails may be readily secured and resiliently seated for absorbing shocks and jars incident to the varying traffic conditions.

15 A further object of the invention is to provide a metallic tie upon which railway rails are resiliently seated at a proper distance apart for the gage of the railroad and with the ties uniformly spaced apart.

20 With these general objects in view, the invention will be fully described in connection with the accompanying drawings and in which like reference characters designate corresponding parts throughout the several views.

In the drawings,

Figure 1 is a vertical transverse sectional view through a railway line illustrating the rails positioned upon a tie of my invention with the tie broken away.

Fig. 2 is a top plan view thereof.

Fig. 3 is an enlarged vertical sectional view taken upon line III—III of Fig. 2.

Fig. 4 is a vertical sectional view taken on line IV—IV of Fig. 3, and

Fig. 5 is a top plan view of an end portion of the tie with the rail and its securing means removed.

40 My invention provides a metal tie having a main body portion 10 rectangular in cross section with its opposite ends formed alike but opposite in arrangement and including a transverse head 11 at each end of the tie of substantially the same cross sectional area as the rail body 10.

A block 12 is provided at each end of the tie slightly inwardly of the heads 11 adapted for engagement with the outer face of the web 13 of an adjacently positioned rail when operatively mounted upon the tie. The end portions of the tie body 10 are longitudinally channeled as at 14 providing parallel side walls 15 while each channel 14 extends into a recess 16 beneath the blocks 12.

55 A clamp 17 is provided for each channel 14 having its base 18 slidably positioned

therein so that the clamps 17 may be slid longitudinally of the tie body 10 toward and away from the blocks 12. The side walls 15 are cut-away as at 19 for accommodating the base 20 of a rail such as 21 while bolts 22 extend through perforations 23 in the base 18 of each clamp 17 and through the recesses 16 and perforations 24 through the outer sides of the heads 11. 60 This arrangement permits the rail 21 to seat with its base 20 upon the bolts 22 providing a slightly resilient seat for the rail because of the resiliency of the bolts 22, the cut-away portions 19 accommodating the cushioned movement of the rail.

65 The head 25 of each bolt 22 is retained and prevented from turning by being positioned in a squared opening 26 at the outer ends of the perforations 23 while nuts 27 70 upon the outer ends of the bolts 22 draw the clamp 17 into close contact with the rail 21 and lock the rail upon the tie. In this manner, two rails 21 are operatively positioned upon the tie body 10 accurately spaced apart 75 for the gage of the road by having the blocks 20 properly arranged upon the body 10. A slight resiliency of the rail seating renders the metallic tie more efficient and long lived while the rails are readily secured thereto and removed therefrom at will.

80 The heads 11 at the opposite ends of the tie which is substantially H-shaped are adapted to have their ends 28 positioned in abutting relations so that a continuous base 90 is provided at the opposite sides of the track serviceable in stabilizing the ties when mounted upon the roadbed. The heads 11 also furnish a suitable mounting means for third rails accurately spacing the same outwardly of the rails 21. The heads 11 may be secured together if desired and employed as a walk for the trackmen when conditions warrant such a use thereof.

85 What I claim as new is:

100 1. A metallic tie having a body rectangular in cross section provided with a longitudinal channel in the upper face thereof, a cross head at the end of the body having passages therethrough communicating with 105 said channel, a block upon said body adjacent the head, a clamp having a portion slidably positioned in said channel adapted for movement toward and away from said block, and resilient bolts extending through 110 said clamp and passages removably secured to the tie body.

2. A device of the class described comprising an elongated metal body having a cross head at the end thereof and an up-standing block inwardly of said head, said head and body being provided with a passage therethrough opening into a channel at the top of the body inwardly of the block, a clamp slidably positioned in said channel portion, and securing bolts through said clamp and head extending outwardly of the latter forming a resilient rail seat beneath said block and clamp.

3. A metallic tie having a cross head at each end thereof, the ends of said heads being adapted for abutting engagement when the ties are arranged equally spaced apart upon the roadbed, blocks upon the tie in-

wardly of said heads, said tie having a longitudinal channel in its upper face inwardly and beneath each block, each head having a 20 passage therethrough communicating with a channel of the tie, a clamp slidably positioned in each channel, said blocks and clamps being adapted to receive rails there-between, resilient bolts extending through 25 said clamps and channels outwardly beyond the heads adapted for the seating of rails thereon, and locking means upon the outer ends of said bolts, the tie at the opposite 30 sides of the channels being cut-away furnishing a clearance for the rails when operatively mounted upon the tie.

In testimony whereof I affix my signature.
HILARY FUDCZKO.
